UNITED STATES PATENT OFFICE.

WILLIAM L. GREGG, OF MILWAUKEE, WISCONSIN, ASSIGNOR TO THE FULLER-WARREN COMPANY, OF MILWAUKEE, WISCONSIN, A CORPORATION OF WISCONSIN.

RANGE.

Application filed December 14, 1925 Serial No. 75349.

Many households find it desirable to have a kitchen heater in addition to the gas range and heretofore it has been customary either to build the heater into the gas range as an integral part thereof, or build it as an entirely separate device. One objectionable feature of building the heater in the gas range as an integral part thereof is that should the stove be moved to another location, it may be entirely too large to fit and thus necessitate the replacement of the entire stove. One objection to the heater as an entirely separate device is that it lacks compactness and requires added floor space and is not as one unit with the gas range.

Having the above objectionable features to kitchen heaters as heretofore constructed in mind, it is an object of this invention to provide an improved heater which is readily applicable to gas ranges to be employed as substantially an integral part thereof and at the same time is capable of being readily detached therefrom.

Another object of this invention resides in the provision of an improved kitchen heater which may be readily applied to gas ranges without necessitating any changes in their construction so that the manufacturing costs are not increased and a combination gas range and kitchen heater developed from any standard gas stove.

It is a further object of this invention to provide an improved kitchen heater of the character described having mounting means capable of being readily engaged in the stove burner section top frame openings normally provided for receiving the mounting lugs of the conventional end shelf.

It is a still further object of this invention to provide improved means for incorporating a kitchen heater as a unit of a gas range which in nowise mars the appearance of the stove and which is capable of ready application to a stove either at the factory or to stoves in use.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have il-

lustrated one complete example of the physical embodiment of my invention constructed according to the best mode I have so far devised for the practical application of the principles thereof, and in which:

Figure 1 is a perspective view of a gas range equipped with my invention;

Figure 2 is a fragmentary, perspective view of one end portion of a stove illustrating the application thereto of the supporting means of my improved kitchen heater;

Figure 3 is a fragmentary, perspective view of an improved kitchen heater embodying my invention, and illustrating the means for supporting the same from the gas range, parts thereof being broken away and in section, and

Figure 4 is a sectional view taken vertically through the adjoining walls of the gas range and kitchen heater on the plane of the line 4-4 of Figure 2.

Referring now more particularly to the accompanying drawings, in which like numerals designate like parts throughout the several views, the numeral 10 designates the main or base frame of a gas range supported by legs 11. The main frame or base is preferably constructed of angle iron bent to approximately the shape of the stove and having its exterior portions preferably concealed by finishing strips or the like 12.

The stove illustrated in the drawing is divided into an oven compartment O and a burner section B, the structure being of the conventional design, and the burner section having a top frame or plate 13 adapted to receive the customary removable grate 14. The frame 13 has depending flanges 15 on its ends in which spaced apertures 16 are provided to receive the attaching lugs, not shown, of an extension or shelf 17 illustrated in dotted lines in Figure 1. The ends of the top frame are identical to permit its use with either left or right hand stoves and the vertical flanges 15 thereof have one or more openings 18 therein to receive means, not shown, for connecting the same with the frame-work of the oven section.

In many households it is desirable that a small kitchen heater be used for maintaining a wood or coal fire as an auxiliary to the gas range and heretofore the kitchen heater has been a separate unit or else embodied in the gas range construction as an integral part thereof. The latter construction is objectionable in that the range is of necessity of con-

siderable length and for that reason is often-times incapable of use when it is moved to a new location. In the accompanying drawings, I have illustrated an improved type of 5 kitchen heater H which is capable of being readily detachably secured to and supported from the gas range at its burner section end so that it becomes incorporated with the stove as a part thereof but at the same time is 10 capable of being readily detached in the event a new location will not accommodate its length.

The heater consists of a fire box 19 beneath which an ash compartment 20 is positioned 15 and has a top plate 21, the inner end of which projects beyond the adjacent side wall 22 and has its edge formed with a downwardly extending flange or rib 28. The wall 22 of the heater is formed with a pair of supporting 20 lugs 24 and an attaching lug 25 adapted to overlie a supporting shelf or bracket 26 carried by the stove frame.

The supporting shelf or bracket is of the 25 construction best illustrated in Figures 2 and 4 and is secured to the vertical portion 27 of the end of the frame 10 at the burner section in place of the finishing strip 12 normally securing the end panel 28 in position. The shelf 26 is preferably of right-angular construction 30 and has apertures 29 in its vertical portion which register with the apertures 30 in the frame 10 to receive attaching bolts 31. Suitable reinforcing ribs 32 extend from the vertical portion of the shelf to projections or 35 lugs 33 extended beyond its horizontal portion to register with the lugs 25 and 24 formed on the heater inner wall.

To install the improved heater, the conventional shelf 17 is detached from the end of the 40 top plate or frame 13 and a supporting rail 34 substituted therefor, having lugs 35 projected therefrom to fit within the openings 16 and provided with upwardly projecting knobs 36 on their inner ends to engage between 45 spaced lugs 37 formed on the under side of the top frame. The supporting rail 34 is adapted to fit flush against the adjacent end wall or flange 15 of the top frame and has an upwardly extending flange 38 slightly spaced 50 from the stove top frame to form a channel or recess 39 in which the depending flange or rib 23 of the heater top fits to thus hang or suspend the heater therefrom. The supporting rail has lateral extensions or projections 55 40 extended therefrom in which openings 41 register with openings 42 in the heater top to receive fastening bolts 43. While the lugs 35 form ample protection against accidental dislodgement of the supporting rail, a bolt 44 60 may be passed through an opening 45 in the supporting rail and the opening 18 normally provided in the vertical portions 15 of the burner section top frame.

When the heater is suspended from the supporting rail in the manner described, the pro-

jections 24 and 25 thereof overlie the projections 33 of the shelf 26 and a bolt or other means 46 is passed through registering apertures 47 in the lug 25 and the central lug 33 to secure the same against accidental dislodgement and the lugs 24 are engaged by leveling screws 48 threaded in openings in the end-most lugs 33 to thus insure the proper leveling of the heater.

The front plate 49 of the heater preferably 75 extends beyond the wall 22 thereof, as at 50, to rest flush with the vertical portion 51 of the burner section, the projection 50 being cut away, as at 52, to accommodate the usual stringer pipe 53.

In equipping a stove either at the time of its manufacture or after its manufacture with my improved heater, the shelf 17 is dispensed with and the supporting rail 34 mounted in its place and the facing plate for the outer end of the frame 10 is removed and the supporting shelf 26 substituted therefor. The heater is then suspended from the rail 34 by engaging its flange 23 in the channel 39 and the leveling screws 48 are then turned to bear against the 85 lugs 24, the bolts 43 and 46 being inserted merely as an extra precaution, although they are not necessary as the heater is firmly supported from the stove with the outermost surfaces of the lugs 33 abutting the wall 22. 95

What I claim as my invention is:

1. In a gas range having a burner section and a top frame for the section, a supporting rail connectible with the top frame, a heater 100 removably supported from the supporting rail and having an interlocking connection therewith, and a shelf structure carried by the range below the supporting rail and engageable with the heater at its inner lower end portion to, with the supporting rail, give 105 support thereto.

2. In a range of the character described having a burner section top frame provided with apertures in its side for the reception of the attaching lugs of a removable shelf, a 110 kitchen heater, lugs engageable in the openings of the top frame in place of the shelf lugs to support the heater therefrom, and means carried by the range cooperating with said lugs and engageable with the kitchen 115 heater at a lower point to assist in supporting the same.

3. In a gas range having a burner section top frame provided with apertures in its end, a supporting member, attaching lugs extending from the supporting member and engageable in the top frame openings whereby said supporting member is connected therewith, a heater, and an interlocking connection between the heater and supporting member 125 whereby the heater is supported from the range.

4. In a gas range having a main base frame and a burner section top frame provided with apertures in its end, a supporting member, 130

attaching lugs extendings from the supporting member and engageable in the top frame openings whereby said supporting member is connected therewith, a heater, an interlocking connection between the heater and supporting member whereby the heater is supported from the range, and means carried by the main frame and cooperating with the supporting member to rigidly mount the heater.

5. In a gas range having a burner section top frame provided with apertures in its end, a supporting member having an upwardly extended longitudinal rib thereon, 15 attaching lugs extending from the supporting member and engageable in the top frame openings whereby said supporting member is connectible therewith, a heater, and a downwardly extended flange on the inner edge of 20 the heater top portion and adapted to be engaged behind the supporting member flange.

6. In a gas range having a burner section top frame provided with apertures in its end, a supporting member having an upwardly 25 extended longitudinal rib thereon, attaching lugs extending from the supporting member and engageable in the top frame openings whereby said supporting member is connectible therewith, a heater, a downwardly extended flange on the inner side edge of the 30 heater top portion and adapted to be engaged behind the supporting member flange, and lugs on the supporting member adapted to be secured to the heater.

35. 7. In a gas range having a main base frame and a burner section top frame provided with apertures in its end, a supporting member having an upwardly extended longitudinal rib thereon, attaching lugs extending from 40 the supporting member and engageable in the top frame openings whereby said supporting member is connectible therewith, a heater, a downwardly extended flange on the inner side of the heater top portion and

adapted to be engaged behind the supporting member flange, a shelf structure securable to the main base frame, and means carried by the shelf structure and cooperating with the supporting member to mount the heater as an integral part of the range.

8. In a gas range having a main base frame and a burner section top frame provided with apertures in its end, a supporting member having an upwardly extended longitudinal rib thereon, attaching lugs extending from the supporting member and engageable in the top frame openings whereby said supporting member is connectible therewith, a heater, a downwardly extended flange on the inner side of the heater top portion and 55 adapted to be engaged behind the supporting member flange, a shelf structure securable to the main base frame, and leveling means carried by the shelf structure and heater to make the heater firm with the range.

9. In a gas range having a burner section and a top frame for the section provided with spaced apertures in one side for the reception of the attaching lugs of a removable shelf, a supporting rail, lugs carried by the rail and 60 engageable in the frame apertures to readily detachably mount the rail from the top frame, and a heater supported from the supporting rail.

10. In a gas range having a burner section and a top frame for the section provided with spaced apertures in one side for the reception of the attaching lugs of a removable shelf, a supporting rail, lugs carried by the rail and 65 engageable in the frame aperture to readily detachably mount the rail from the top frame, a heater, and means providing an interlocking connection between the heater and supporting rail whereby the heater is removably supported from the rail.

In testimony whereof I affix my signature.

WILLIAM L. GREGG.
